MANUFACTURE OF LOOPED FABRICS

Fritz Seiler, Auvernier, near Neuchatel, Switzerland, assignor to Edouard Dubied & Cie (Societe Anonyme), Neuchatel, Switzerland

Application October 9, 1951, Serial No. 250,442

Claims priority, application Switzerland October 12, 1950

5 Claims. (Cl. 66—6)

My present invention relates to a method for manufacturing looped fabrics by means of two rows of staggered needles which throw off their loops towards each other. My present method is characterised in that, subsequently to yarn-sinking or drawing which is carried out alternately by individual needles of the two rows, the individually movable needles of one row are moved in turn forwardly and rearwardly for the purpose of looping, and in that, independently thereof, all the needles of the other row are actuated together for the purpose of throwing off the loops; the whole with a view of manufacturing a double-faced looped fabric which on one side comprises knit loops and, on the other side, sunk or drawn loops.

For economical and, above all, practical reasons, no use is made of conventional flat knitting machines having two needle beds.

When using my present method, racked-, openwork-, color- and fancy-patterns are obtainable in a very simple way and manner.

By virtue of disengaging the needles of one row from the loop-sinking or drawing means, the apparatus constructed for carrying out my present method is suited for manufacturing plain or common hosiery or single-faced inlaid fabric in solid colors.

The said knitting apparatus also forms part of my present invention and comprises a conventional yarn guide which feeds the yarn alternately to individual needles in a needle bed and to individual needles in a needle bar, a cam box being reciprocated along the needle bed to move the individually-movable needles in the needle-bed passages one after another forwardly and rearwardly and to actuate the needles of the needle bar, through relative movement of the latter with respect to the other needle row, simultaneously but separately from the needles movable in the needle bed.

For producing color-, fancy-, or openwork patterns, suitable latch needles are provided which are rockably-mounted in the needle bar and which are adjustable, according to pattern, in the inoperative and operative positions. The said needle bar by conventional means conveniently is rackable laterally and vertically with respect to the other needle row.

The needle bar—for the purpose of manufacturing plain stitch hosiery or single-faced inlaid fabrics with one-and-one or two-and-two borders, as desired—suitably is movable out of the operating range, and the cam box comprises a stationary and a swingable cam, these two cams being reversible with respect to the needles for the purpose of varying the function after removing the carriage from its guides.

My present method as well as the knitting apparatus for carrying out said method shall be explained, by way of example, with the aid of the accompanying drawings in which—

Fig. 1 shows a side view of the apparatus,

Fig. 2 illustrates the needle position during movement of the cam box and yarn guide in direction of the arrow

A along the needle bed for the purpose of producing double-face looped fabrics.

Fig. 3 depicts the needle position for transferring the loops by means of a hook from the bar needles to the bed needles,

Fig. 4 is a top plan view of the cam box, in which the base plate is shown in dash-and-dot lines, it being assumed that the said plate is moved in direction of the arrow A to produce plain hosiery,

Fig. 5 is a top plan view similar to Fig. 4, but under the assumption that the cam-box base plate is moved in direction of the arrow B,

Fig. 6 is another top plan view similar to Fig. 4, in which, however, the cams are reset, it being assumed that the plate is moved in direction of the arrow A to produce one-face inlaid fabrics, and

Fig. 7 is still another top plan view, similar to Fig. 6, but under the assumption that the plate is moved in direction of the arrow B.

In Fig. 1, the numeral 1 designates the frame for the needle bed 2 of which the latch needles 3 in operation are individually and successively moved. The carriage 5 and the cam-box plate 6 together are movable along the needle bed 2 in two guide rails 4. On the plate 6 are disposed two cams 7 and 8. A handle 9 serves for moving the carriage 5 along the needle bed 2. Numeral 10 designates the thread-guide carrier on carriage 5, which comprises the feeder 11 for the draw-thread 12. In the needle bar 13 at 15 are rockably mounted the latch needles 14.

The needle bar 13 at both ends has a handle 16 for moving the bar on guides vertically to form sunk loops and, horizontally, to obtain racked patterns. Numeral 17 is a bail which is laterally withdrawable from the bar 13 to selectively position the needles 14, for which purpose the non-operative needles 14 are rocked on the elongated pin 15 to the position shown in dash-and-dot lines in Fig. 1. An iron band 18 rigidly secured to frame 1 serves as stop for the operative needles 14.

To manufacture a two-face looped fabric, the needles 3 and 14 of the two rows have to be in their operative position, and the needles 3 in bed 2 have to be engaged to the cams 7 and 8 as shown in Figs. 4 and 5 respectively, whilst the needles 14 of bar 13 (which needles are staggered with respect to the needles 3) are in the position shown in Figs. 1 and 2. When moving the carriage 5 by means of handle 9 in the direction of arrow A in Figs. 2 and 4, i. e. from left to right, the feeder 11 delivers the draw-thread 12 to all the operative needles 3 and 14. As in the case of conventional knitting machines, the needles 3 are successively and in sequence moved forwardly and rearwardly in the needle-bed passages. The thread 12 thereby is caught by the hooks of the needles 3, and the loops formed by means of the thread then are passed through the previously formed needle loops which now slide over the needle latches which have been closed thereby, so as to produce knit loops on the respective fabric side. At the same time, the thread by means of thread 12 is sunk through the needles 14 of bar 13.

On completion of the stroke of carriage 5, the needle bar 13 by means of the two handles 16 is moved downwardly and upwardly, whereby the needle loops situated rearwardly of the latches of their needles 14 close the latches and are thrown off onto the loops situated in the needle hooks. In this way are formed a row of sunk loops, i. e., loops as formed in conventional knitting frames. The carriage 5 then is moved in direction of the arrow B in Fig. 5, i. e. from right to left, to repeat the operation.

By virtue of simultaneously casting off the needle loops through all the latch needles 14, as is customary in knit-

ting, a very regular loop structure is obtained in a simple manner.

The apparatus described permits the execution of any patterns desired. By selecting the needles 14 provided on the needle bar 13 and exchanging the feeder 11, there may be produced color and fancy patterns for example. In Fig. 3 is shown a position of the needle bar 13 or, respectively, of the needles 14 from which the loops by means of a hook are transferred to the adjacent needles 3 of the needle row of the bed 2.

It also is possible to produce fabrics of common hosiery or single-faced inlaid fabrics with a double-faced one-and-one or a two-and-two border.

The two-face rib is made from the two kinds of loops in the manner described above. On completion of the rib, the last row of sunk loops 19 is transferred to the hooks of the needles 3 (Fig. 3). After the needle bar 13 has been moved out of the operating range, either common hosiery or single-faced inlaid fabrics are produced with the aid of the needles 3 of bed 2.

Common hosiery is produced in the positions shown in Figs. 1, 4 and 5, of feeder 11 and cams 7 and 8. For producing single-faced inlaid fabrics, however, the carriage 5 after having been moved out of the range of the rails 4, is turned through 180° and reinserted into the rails 4. The carrier 10 with feeder 11 then is outside the working range of the apparatus, as shown in dash-and-dot lines in Fig. 1, and the cams 7 and 8 are correspondingly reversed with respect to each other, i. e. as shown in Figs. 6 and 7. All the needles 3 of bed 2 are advanced in their passages by means of a straight edge until the needle loops hanging from the needles 3 are situated to the rear of the open needle latches. The threads then are inserted into the needle hooks in accordance with the desired inlaid color pattern, just as in the case of an inlay machine having a needle bed. To produce the loop row, the carriage 5 with the cams 7 and 8 then is moved in direction of the arrow A in Fig. 6, i. e. from left to right along the bed 2. When the carriage 5 has arrived on the right-hand side of the apparatus, the threads are again put in the needle hooks, and the carriage is moved in direction of the arrow B in Fig. 7 back to its initial position on the left-hand side of the apparatus. After each stroke of the carriage 5, the cam 8 is automatically tilted on its pivot pin into another position, as indicated in Figs. 6 and 7.

In another embodiment, not shown, the rocking cam 8 is replaced by two conventional movable cams.

What I claim as new and desire to secure by Letters Patent is:

1. Method for the manufacture of knit goods by means of two rows of staggered latch needles which drop their loops in opposite directions to each other, one of said rows being a horizontal row of needles and the other a vertical row of needles comprising the steps of feeding a thread by a feeder to the horizontal row of needles and

to selected needles of the vertical row which are in operative position, moving the needles of the horizontal row forwardly and backwardly in succession by cams to produce knit loops and subsequently moving all the selected needles of the vertical row simultaneously to form sunk loops.

5 2. A knitting machine for manufacturing knit goods comprising horizontal and vertical rows of staggered latch needles which drop their loops in opposite directions to each other, a needle bed for the horizontal row 10 of needles, feeder means for feeding thread to the horizontal row of needles and to selected needles of the vertical row which are in a working position relative to the needles of the horizontal row, a slideable carriage 15 movable over said bed, a cam plate, cam means on said plate movable with said slideable carriage so as to move the needles of the horizontal row of needles forwardly and backwardly in said bed one after another to form knit loops and a needle bar supporting all of the needles of the 20 vertical row and which is movable upwardly and downwardly and which serves to move selected of the vertical needles all simultaneously to form sunk loops.

25 3. A knitting machine as set forth in claim 2 in which for the purpose of obtaining racked patterns and effects involving loop transfers handle means are provided for moving the needle bar and the latch needles supported by the needle bar vertically as well as laterally relative to the horizontal row of needles, and means for guiding said needle bar for lateral and vertical movement.

30 4. A knitting machine as set forth in claim 2, including means for tiltably supporting each of the latch needles carried by said needle bar from said bar so that selected ones of such needles may be swung individually from an operative into an inoperative position on said needle bar and vice versa for the purpose of producing color 35 and fancy patterns.

40 5. A knitting machine as set forth in claim 2 in which for the purpose of manufacturing common hosiery and single-faced inlaid fabrics with one-and-one or two-and- 45 two borders as may be desired the needle bar is movable out of the operating range, and in which said cam means includes a fixed cam and a pivoted cam, said two cams being reversible with respect to the needles of the horizontal row for operating the latter as required respectively for manufacturing said common hosiery and said single-faced inlaid fabrics.
